CLAIM

The ornamental design of a tray for the growing of seedlings, as shown and described.

DESCRIPTION

FIG. 1 is a perspective view of a tray for the growing of seedlings showing my new design;

FIG. 2 is a top plan view thereof;

FIG. 3 is a bottom plan view thereof;

FIG. 4 is an enlarged elevation view of one side thereof, the other side being a mirror image thereof; and,

FIG. 5 is an enlarged elevation view of one end thereof, the other end being a mirror image thereof.
